UNITED STATES PATENT OFFICE.

HENRY ARNOLD GREAVES AND HARRY ETCHELLS, OF SHEFFIELD, ENGLAND.

ELECTRIC FURNACE.

1,257,997.

Specification of Letters Patent.

Patented Mar. 5, 1918.

Application filed March 1, 1917. Serial No. 151,635.

To all whom it may concern:

Be it known that we, HENRY ARNOLD GREAVES and HARRY ETCHELLS, B. Met., subjects of England, residing at 25 Raven road, 5 Sheffield, and 231 Oakbrook road, Sheffield, in the county of York, respectively, have invented new and useful Improvements in Electric Furnaces, of which the following is a specification.

10 Our invention relates to a method of distributing two phase and three phase currents to electric arc furnaces and resistance furnaces, and consists in effecting the distribution in such a manner that the supply 15 phases tend to have balanced loads.

Our invention will be better understood on reference to the accompanying drawings in which—

Figure 1 shows our invention as applied 20 to a three phase supply system, and

Fig. 1^a is a diagrammatic sketch of the arrangement of primary windings.

Fig. 2 shows our invention as applied to 25 a two phase supply system.

The same letters refer to similar parts throughout the several views.

A furnace as shown in Fig. 1 having two top electrodes or groups of electrodes, *a*, *b*, and a conducting hearth or bottom electrode, *c*, is connected with the low tension terminals of three single phase transformer windings OA, OB, OC which are grouped in "star" fashion so that one low tension terminal of each transformer is connected to 30 the star point O, and the other low tension terminal to the respective electrodes, *a*, *b*, and *c*.

The primary windings of this transformer system are grouped in delta or mesh connection as shown in Fig. 1^a.

The two transformers OA, OB are identical in power and transforming ratio, but the secondary voltage OC must be less than OA or OB. The exact voltage OC varies according to the resistance of the bottom electrode *c*.

By means of an auto transformer, or tappings incorporated in the secondary windings of the transformer OC or the corresponding primary winding, the secondary voltage can be varied until the loads on the primary supply phases are exactly balanced, assuming that the currents through electrodes *a* and *b* are equal.

55 By varying the voltage OC the amount

of current taken by the electrode *c*, can be varied, with only a slight displacement of the balance of the primary phases. This results in a passage of more or less current between the electrodes *a*, *b*.

In Fig. 2 is shown an arrangement of transformers whereby two phase currents may be supplied to such a furnace of the type herein referred to, in such a manner that one top electrode cannot be moved without affecting both phases of the supply system. From this figure it will be seen that the two top electrodes *a* and *b* are each connected to the opposite ends of the low tension winding of a transformer AB supplied by one phase of a two phase supply. One terminal of the low tension winding of another transformer D is connected to the middle point O of the low tension winding of the transformer AB; the other terminal 70 being connected to the furnace bottom or to the lower electrode *c*. This last named transformer is separately excited by the other phase of the two phase supply system.

If the first mentioned transformer AB has a secondary voltage between its terminals which is twice the secondary voltage between the terminals of the transformer D, the two phases of primary supply will be equally loaded, when the adjustment of the two top electrodes is such that equal currents pass through each electrode. The secondary voltage of the transformer AB may be less than twice the secondary voltage between the terminals of the other transformer D, when 85 resistance is interposed in the bottom electrode, but is always greater than the secondary voltage of said other transformer.

From the foregoing it will be seen that our improved arrangement is substantially 95 different from the two phase arrangements usually employed wherein two equal single phase transformers are each connected to a separate phase of a two phase supply, thus enabling one phase to be loaded many more 100 times than the other without the one phase affecting the load on the other phase.

It will also be seen that in the foregoing described methods of arranging transformers, no short circuiting can occur between 105 either of the top electrodes and the bottom, without the ensuing rush of current having to traverse two transformers in series. This has a considerable damping or choking effect in the extent of the current overload, and 110

minimizes the extent of sudden overloads on the supply system which constitute a serious drawback to most other types of furnace.

Having now described our invention what we claim as new and desire to secure by Letters Patent is:

1. In electric arc or resistance furnaces having upper and lower electrodes, the improved method of distributing three phase currents so that the supply phases have balanced loads, consisting in the arrangement of three single phase transformers grouped in "star" fashion, and having the primary windings grouped in delta or mesh connection, so that the two transformers connected to the two upper electrodes or groups of electrodes are identical in power and transforming ratio, while the voltage of the transformer connected to the lower electrode is less than either of the other two, the exact voltage varying according to the resistance of the lower electrode in the manner and for the purposes substantially as herein described and illustrated.
2. In electric arc or resistance furnaces having upper and lower electrodes varying the secondary voltage in the transformer connected to the lower electrode by means of an auto-transformer or primary tappings incorporated in said transformer, whereby the loads on the meshed primary supply phases are exactly balanced, when the currents through the upper electrodes are equal, in the manner and for the purposes substantially as herein described.
3. In electric arc or resistance furnaces having upper and lower electrodes the improved method of distributing two phase currents so that both supply phases are always loaded when either electrode carries current, consisting in connecting the two upper electrodes or groups of electrodes to the opposite ends of the low tension winding of a transformer supplied by one phase of a two phase supply, and connecting the lower electrode to one terminal of the low tension winding of another transformer excited by the other phase of the two phase supply system and which has its other terminal connected to the middle point of the low tension winding of the first named transformer, in the manner and for the purposes substantially as herein described.
4. In electric arc or resistance furnaces having upper and lower electrodes the arrangement of the transformer connected with the upper electrodes, with a secondary voltage between its terminals which is twice

or less than twice (if resistance be interposed in the lower electrode) the secondary voltage between the terminals of the other transformer, but always greater than the secondary voltage in said other transformer whereby the two phases of primary supply are equally loaded when equal currents pass through each of the upper electrodes, in the manner and for the purposes substantially as herein described.

5. In electric arc or resistance furnaces having upper and lower electrodes, worked by two phase or three phase currents, the improved arrangement and grouping of transformers whereby the supply phases always tend to have balanced loads, substantially as herein described and illustrated on the accompanying sheet of drawings.

6. An electric arc or resistance furnace having upper and lower electrodes wherein considerable resistance can be introduced through the bottom electrode without mingling phases and impairing the power factor of the system, substantially as herein described and illustrated.

7. The method of distributing alternating current to an arc or resistance furnace having upper and lower electrodes, which consists in connecting the secondary circuits of a transformer system to the electrodes of the furnace, the secondary windings of the transformer system being such that the load on the primary supply phases is balanced.

8. The method of distributing alternating current to an arc or resistance furnace having upper and lower electrodes, which consists in connecting the secondary circuits of a transformer system to the electrodes of the furnace, and regulating the voltage of one of the secondary windings of the transformer system to balance the load on the primary supply phases thereof.

9. The combination of an electric furnace having upper and lower electrodes, a transformer system having current generated in its secondary windings, one or more of the secondary windings having a lower voltage than the others, and connections between terminals of the secondary windings and the respective electrodes.

In testimony whereof we have signed our names to this specification in the presence of two subscribing witnesses.

HENRY ARNOLD GREAVES.
HARRY ETCHELLS.
